DAVID S. WILLIAMS, OF PORTLAND, OREGON

ADJUSTABLE FLOOR DRAIN

Application filed June 5, 1928. Serial No. 283,002.

This invention relates to drains and has particular reference to drains which are permanently emplaced in a floor, roof, bottom of a tank, or the like.

5 The common type of floor drain consists of a sleeve permanently set into a floor of concrete, metal, stone or the like, this sleeve being connected with a waste-pipe or trap beneath the floor, and having an intake 10 strainer in the form of a perforated plate usually set level with the floor, or, more often, in the bottom of a depression or safe pan for the collection of the liquid. Frequently, the intake strainer is not set level 15 with the bottom of the safe pan so that a certain amount of liquid collects in the pan and cannot flow away, and when a large quantity of liquid is supplied at once the safe pan floods because the drain is unable to carry 20 away the excess liquid rapidly.

It is the principal object of this invention to provide a drain which prevents flooding of the safe pan when a large quantity of liquid is supplied, by removing the greater 25 portion of liquid from a point above the level of the safe pan and conveying it immediately to a point well below the bottom of the pan, while the liquid in the pan below the elevated opening of the drain flows through 30 suitable openings around the drain tube and directly into the waste pipe or trap. Thus a drain is provided which discharges liquid to the full capacity of the waste pipes without flooding and with great rapidity, whereby 35 fewer drains may be employed, each of which remains dry and sanitary when not in use because no liquid is allowed to collect in the safe pan.

In accordance with this object the usual 40 floor drain sleeve is provided with an auxiliary sleeve having weep slots for the discharge of liquid below the level of the drain tube which is adjustably mounted in this sleeve upon spaced projections formed in the 45 interior walls thereof. The drain tube is provided with interrupted spiral adjusting bars which rest upon the projections in the auxiliary sleeve. By means of these spiral bars the drain tube may be adjusted so that 50 the intake opening thereof is elevated any de-

sired distance above the level of the safe pan, while the discharge opening of the tube lies well below the bottom of the pan. Accordingly, when large quantities of liquid are supplied to the drain, the greater portion 55 thereof is removed from a point above the level of the safe pan and conveyed directly into the waste pipe or trap below the floor, while the liquid in the safe pan below the level of the drain tube intake flows along the 60 outside of the tube through the weep slots and interrupted portions of the adjusting bars. The interrupted portions of the adjusting bars also serve as release slots whereby 65 the drain tube may be readily lifted out of the sleeve, the supporting projections on the sleeve passing through these slots when the tube is being removed.

For a better understanding of the invention, reference is made to the accompanying 70 drawings, in which

Fig. 1 is a vertical section through the improved drain of this invention;

Fig. 2 is a plan view of the auxiliary sleeve; 75 and

Fig. 3 is a perspective view thereof.

In these drawings, numeral 10 designates the body or main sleeve of the drain which is formed cup-shaped on its upper surface so as to provide the customary safe pan, this main body being emplaced in concrete as shown, or otherwise fastened to a wooden or metal floor, roof, tank bottom, or other surface. Over the top of the main body is placed the water-proofing 11, which may be lead sheathing or other sheet metal, or merely some composition material through which only one hole is cut for the reception of the other parts of the drain. The upper and lower openings of body 10 are preferably threaded as shown, the lower threads 12 being adapted to receive the waste pipe or trap connection, disposed beneath the floor or other surface, while the upper threads 13 are adapted to receive an auxiliary sleeve or lock screw 14.

This sleeve or lock screw 14 is illustrated particularly in perspective in Fig. 3 and in plan in Fig. 2. The interior surface of the tubular portion of the sleeve 14 is provided 100

with a series of longitudinal weep slots 15, which communicate with weep slots 16 cut through a flange 17 formed on the upper end of the tubular sleeve 14. When this sleeve is screwed down into threads 13 of the main body 10, the flange 17 fits down upon slip washer 18 placed upon the water proofing 11, so that the joint between the body 10 and the sleeve 14 is absolutely watertight, any seepage water flowing through weep slots 16 and 15 down the inside of the sleeve 14.

The interior surface of sleeve 14 is provided at spaced intervals with several rows of integral projections 19 preferably placed between the interior weep slots 15 as shown particularly in Figs. 2 and 3. These projections 19 are preferably staggered with respect to each other in the manner illustrated particularly in Fig. 1, so that they are not all in the same planes. Accordingly, the auxiliary sleeve or lock screw 14 appears in perspective as shown in Fig. 3.

Inserted in the opening of auxiliary sleeve 14 is the drain tube 20, which is preferably bellied at its upper end as shown, and provided with a flange 21. This upper end, being the intake opening of the drain tube, is provided with a suitable strainer 22, which is preferably of the bar type as illustrated in Fig. 1. This strainer may be secured in place in any suitable way. The exterior surface of drain tube 20 is provided with a plurality of adjusting bars 23, which are preferably cast integral with the drain tube 20 and are preferably made slanting, as shown, in the form of a spiral. These bars are interrupted at 24 so as to form slots longitudinally of the exterior surface of the tube 20, but these slots are not co-linear, but are staggered as illustrated in Fig. 1.

Accordingly, when drain tube 20 is inserted in auxiliary sleeve 14, the adjusting bars 23 thereof are engaged by projections 19 so that the drain tube is supported by these projections. Inasmuch as adjusting bars 23 are made slanting, the elevation of the intake opening of the drain tube may be adjusted with respect to the safe pan or the top of auxiliary sleeve flange 17 merely by rotating the drain tube 20. If a higher elevation of the tube is desired, it is rotated from left to right, and if it is desired to depress the tube into sleeve 14, it may be rotated from right to left.

The slots 24 in adjusting bars 23 allow the drain tube 20 to be inserted rapidly without the necessity of screwing it down, because the tube may be inserted so that projections 19 pass through slots 24 until the required elevation of the drain tube is obtained and then the tube is turned slightly so that the projections 19 engage the bars 23. In order to thus insert the tube 20 and likewise remove it, it must be worked slightly

from left to right because the slots 24 are staggered as shown. This staggering is done so that if, in adjusting, the tube should slip downwardly, it would stop at the next succeeding adjusting bar and not fall all the way through, which would take place if the slots 24 were in alignment. Obviously, the drain tube 20 may be inserted as far as it will go, so that flange 21 will rest upon flange 17 of sleeve 14, in the manner illustrated in phantom in Figure 1.

In operation, the drain tube 20 may be elevated to any desired point merely by adjusting the tube in auxiliary sleeve 14 in the manner described. Assuming that the drain is to be supplied with a large amount of water or other liquid so that the safe pan would ordinarily overflow in the common type of drain because the water is not carried to a point substantially below the point where it is introduced into the drain; in the new drain, however, the greater amount of the liquid is withdrawn through strainer 22 from a point substantially above the surface of the safe pan and conveyed through drain tube 20 into the waste pipe or trap below the floor. The water in the safe pan below the intake of drain tube 20, however, does not collect or tend to flood, but flows through weep slots 16 and 15 between the inside surface sleeve 14 and the outside surface of drain tube 20 and into the waste pipe or trap below. In order that adjusting bars 23 do not close off the annular passage between drain tube 20 and sleeve 14, the slots 24 also cooperate to provide a weep slot for the passage of the liquid so that it does not accumulate in the drain pan but may flow freely into the waste pipe or trap below. In any case, no matter what the elevation of drain tube 20 may be, the liquid is carried well below the intake opening thereof by the elongated tube portion thereof so that no flooding can occur. Furthermore, as weep slots 14 are made flush with the bottom of the safe pan, no liquid can accumulate or remain in the drain pan, as often occurs in the ordinary type of drain, because of a flange on the drain which rises above the bottom of the drain pan.

It will be seen that the new drain provides a very inexpensive and effective drain which removes liquid from a floor or other surface without flooding, and to the full capacity of the waste pipes below the floor to which the drain is connected. Because of flooding, the drains in common use are slow in removing liquid and several of them must be used at one time in order to remove the liquid effectively. By providing a drain of this invention, on the contrary, several of the old types of drains may be entirely eliminated, because the new drain is as effective as a number of the old drains for removing the same amount of liquid. Even when the drain tube 20 is depressed to its lowermost

position as shown in phantom in Fig. 1, the liquid will be rapidly carried away because it flows through weep slots 16 in flange 17 as well as through strainer 22 to a point well 5 below the surface in which the drain is mounted.

Although a specific embodiment of the invention has been illustrated and described, it is to be understood that the embodiment is 10 susceptible to many changes within the scope of the invention. Among such changes may be the variation of the pitch of the slanting adjusting bars 23, whereby a more rapid adjustment is obtainable, or these bars may be 15 made horizontal, the adjustment being obtained by working the tube either up or down so that the projections 19 pass through slots 24, and then rotating the tube slot slightly when the required adjustment is obtained so that adjusting bars 23 rest upon the 20 projections 19 at that point.

I claim:

1. In a drain, the combination of a tubular sleeve adapted to be connected to a waste pipe, said tubular sleeve having a plurality of weep slots in the interior of the sleeve, a plurality of projections spaced along the aforesaid interior of the sleeve, and a drain tube adjustably supported within the sleeve 30 upon said projections.
2. In a drain, the combination of a tubular sleeve adapted to be connected to a waste pipe, said tubular sleeve having a plurality of weep slots in the interior of the sleeve, and 35 a plurality of drain grooves communicating therewith a plurality of projections spaced along the aforesaid interior of the sleeve, and a drain tube supported within the sleeve upon said projections.

40 In testimony whereof I affix my signature.
DAVID S. WILLIAMS.
